ALBERT B. CRAWFORD, OF CHICAGO, ILLINOIS.

ENVELOP-SEALING MACHINE.

1,238,111.

Specification of Letters Patent. Patented Aug. 28, 1917.

Application filed August 11, 1915. Serial No. 44,894.

To all whom it may concern:

Be it known that I, ALBERT B. CRAWFORD, a citizen of the United States, residing at Chicago, in the county of Cook and State 5 of Illinois, have invented certain new and useful Improvements in Envelop-Sealing Machines, of which the following is a specification.

This invention relates to envelop sealing 10 machines, and belongs more specifically to that type of such machines which employ a rotary moistening blade that dips into a water well and engages beneath the gummed flap of the envelop to moisten the latter and, 15 in coöperation with a feed roll, advances the envelop endwise into the nip of a pair of sealing rolls by which the moistened flap is pressed down onto the body of the envelop and the sealed envelop is delivered from the 20 machine.

The general object of the invention is to produce a machine of this type characterized by increased simplicity and reliability of operation as compared with known machines. Another object is to provide a machine wherein the envelopes to be sealed may be mounted in a bunch or stack on the machine and will be successively engaged and sealed by the latter, without requiring any 25 special positioning or other handling of the individual envelopes to insure their being properly handled by the machine. This latter is a very desirable feature in a machine of this sort, since it represents a great 30 saving of time and labor in the manipulation of the machine.

Other objects and many of the attendant advantages of my invention will be readily apparent to those skilled in the art from a 40 consideration of the following detailed description taken in connection with the accompanying drawings wherein I have illustrated one practical and approved embodiment of the invention, and in which—

45 Figure 1 is a side elevation of the complete machine, showing the foremost of a bunch of envelopes in position to be sealed;

Fig. 2 is a sectional view at right angles to Fig. 1 as seen on the line 2—2 of the latter figure;

Fig. 3 is an end elevation as viewed from the right of Fig. 1;

Fig. 4 is a top plan with the top stationary plate of the machine removed to disclose the underlying parts.

Referring to the drawings, 5 designates

the base plate, and 6 designates as an entirety the frame structure resting on the base plate 5 and in which the several operative parts are mounted. 7 designates a 60 water well at one end of the base 5, and 8 designates a feed chute for unsealed envelopes that is secured by screws 9 to one side wall of the water well 7 and is adapted to support a bunch of envelopes standing on 65 their lower edges.

In suitable bearings 10 and 11 of the main frame is journaled a horizontal shaft 12 carrying on its outer end a crank arm 13 and handle 14. Keyed to the inner end of 70 shaft 12 is a moistening blade 15. This blade, as will be seen by reference to Fig. 1, is not a complete circular disk (as is common in machines of this type) but has an arcuate periphery 15' comprising only a 75 segment of a circle and a slightly inclined or conical face, its opposite face being flat or preferably concave. Coöperating with the moistening blade 15 is a vertical conical roller 16 journaled at its lower end in a 80 bearing 17 formed on the shaft bearing 10 and at its upper end in a block 18 that is slidably mounted in and transversely of a top plate 19; the bearing block 18 being normally urged inwardly by a spring 20 to 85 thereby maintain the roller 16 yieldably in rolling contact with the conical or inclined face of the moistening blade 15.

Beyond the moistening blade and feed roller are mounted on upright spindles 20 90 and 21 a pair of rubber covered sealing rolls 22 and 23 respectively. It will be noted by reference to Fig. 3 that the spindles 20 and 21 are not vertical but are slightly inclined from the vertical, for a 95 purpose hereinafter disclosed. The spindle 20 is fixedly journaled in suitable bearings in the base 5 and top plate 19, while the spindle 21 is journaled in lower and upper blocks 24 and 25 (Fig. 3) that are slidably 100 mounted in and movable transversely of the top base 5 and plate 19 respectively and are elastically forced inwardly by springs 26 and 27, whereby the roller 23 is yieldably 105 held in rolling contact with its mating roller 22.

Fast on the drive shaft 12 is a bevel gear 28 that meshes with a bevel pinion 29 keyed on one end of a horizontal shaft 30 that is supported in a suitable bearing 31 of the 110 frame and carries at its opposite end a bevel pinion 32 meshing with and driving a bevel

pinion 33 keyed to the spindle 20 of the sealing roll 22. By the mechanism last described, the turning of the crank 13 simultaneously actuates the moistening blade and the sealing and delivery rolls.

Secured to the inner face of an inclined portion of one of the side walls of the water well 7 is a squeegee 34 (Fig. 2) that rubs against the flat peripheral portion of the outer face of the moistening blade to prevent the moistening of the contents of the envelop during the engagement of the moistening blade with the latter. Also supported by a depending bracket 35 (Fig. 1) from the top plate 19 is another squeegee 36 that rubs against the surface of the feed roller 16 to prevent the application of moisture to the outer side of the flap of the envelop. Secured to the upright portion of the main frame in which the transmission shaft 30 is journaled is a thin elastic wiper blade 37 (Fig. 4) that coöperates with a flat vertical guide wall 38 of the frame to iron out the moistened portion of the flap and exclude any surplus moisture.

Integral with the top plate 19 and located in advance of the feed roller 16 is a horizontal channel guide 39 that is engaged by the upper edge of the envelop at the beginning of the flap-moistening and feeding operation as the latter travels from the moistening and feeding devices to the sealing rolls.

In the operation of the machine, a bunch of unsealed envelops is stacked up, flap sides foremost, on the feed chute 8, their lower edges resting on the latter; and to promote the uniform forward feeding of the envelops along the chute a follower device is preferably employed, although hand pressure by the operator may be used. In Fig. 2 I have indicated in dotted lines such a follower device consisting simply of a roller 41 that rests against the rearmost envelop of the stack and, since the chute 8 is inclined, exerts a light and uniform gravity effect tending to crowd the stack of envelops toward the lower end of the chute. The upper forward corner of the foremost envelop rests against the surface of the feed roller 16, as indicated in Figs. 1 and 2, so that the effect of the follower is to not only continuously advance the bunch of envelops as the latter are successively withdrawn and put through the machine, but also to slightly bend the envelops so as to cause the depending flap of the foremost envelop to swing away from the body of the envelop and overhang the path of travel of the periphery of the moistened blade. This latter turns in the direction indicated by the arrow in Fig. 1 so that, as the moistening blade rotates, one point or corner thereof, constituting the pick-up portion indicated by 15^a in Fig. 1, enters behind the flap, picks the foremost envelop up carrying its upper edge into en-

gagement with the channel guide 39, and as soon as the point 15^a of the moistening blade reaches the feed roll 16 the flap is in the nip of said parts and the envelop is advanced endwise between them. The inclined or conical surface of the moistening blade, which dips in the water well, carries up sufficient water to thoroughly moisten the gummed side of the flap as the latter travels between said moistening blade and the feed roll 16. As the envelop advances, the flap overhangs the inner side of the thin wall 38 while the body of the envelop overhangs the outer side, so that said wall 38 protects the contents from any surplus moisture (which is removed by the brush or squeegee 37) until the forward end of the envelop has come into the nip of the sealing rolls 22 and 23. In passing through the latter rolls the moistened flap is securely sealed to the back side of the body of the envelop; and in passing between said rolls the envelop is shifted from a substantially vertical position to a slightly inclined position, so that as the envelop is shot forward from between said rolls it comes to rest always face up on the table or other support on which the machine is mounted.

It is believed that the nature, construction, mode of operation and advantages of my invention will be readily understood from the foregoing description; and since it is obvious to those acquainted with the art that the attainment of these advantages is not dependent upon the precise specific form of apparatus shown and described, I do not limit the invention to the particular embodiment illustrated, but reserve the right to make such detail variations and changes as may fairly fall within the spirit and purview of the invention as defined in the appended claims.

I claim:

1. In an envelop sealing machine, the combination of a frame, a water well, a rotary moistening blade having an arcuate segmental periphery dipping into said well, means for supporting an envelop with its flap overhanging the path of the periphery of said blade, means coöperating with said blade for feeding the envelop forward, and sealing means located beyond said blade.

2. In an envelop sealing machine, the combination of a frame, a water well, a rotary moistening blade having an arcuate segmental periphery dipping into said well, a laterally extending chute opposite said blade adapted to support a bunch of envelops standing on edge, a follower device serving to press the envelops toward said blade and cause the flap of the foremost envelop to overhang the path of the periphery of the latter, means coöperating with said blade for feeding the envelop forward, and sealing means located beyond said blade.

3. In an envelop sealing machine, the combination of a frame, a moistening water well carried thereby, a rotary blade having an arcuate segmental periphery mounted in said frame, means for supporting an envelop with its flap overhanging the path of travel of the periphery of said blade, means for coöperating with said blade for feeding the envelop forward, and sealing means located beyond said blade.

4. In an envelop sealing machine, the combination of a frame, a water well, a rotary moistening blade having an arcuate segmental periphery and an inclined side dipping into said well, a laterally extending chute opposite the other side of said blade serving to support a bunch of envelops standing on edge, a follower device serving to press the envelops toward said blade and cause the flap of the foremost envelop to overhang the path of the periphery of the latter, a conical roller coöperating with the inclined side of said blade to feed the envelops forward, and sealing means located beyond said blade and roller.

5. In an envelop sealing machine, the combination of a frame, a lateral chute for supporting a bunch of unsealed envelops standing on edge, a water well, a rotary blade having an arcuate segmental periphery dipping into said well and operating at each rotation to pick up the foremost envelop, moisten the gummed flap thereof and feed it forward, a feed-roll yieldably held in rolling contact with said blade and coöperating with the latter in feeding the envelop forward, a guide for the upper edge of the envelop in advance of said feed-roll,

and a pair of sealing rolls located beyond said feed-roll.

6. In an envelop sealing machine, the combination of a frame, a lateral chute for supporting a bunch of unsealed envelops standing on edge, a water well, a rotary moistening blade dipping into said well and operating at each rotation to pick up the foremost envelop, moisten the gummed flap thereof and feed it forward, a feed-roll yieldably held in rolling contact with said blade and coöperating with the latter in feeding the envelop forward, a guide for the upper edge of the envelop in advance of said feed-roll, a pair of sealing rolls located beyond said feed-roll, a vertical guide wall located between said feed-roll and sealing rolls and engaging the envelop between the body and flap thereof to direct it into the nip of the sealing rolls, and a wiper engaging the outer side of the flap as the latter passes along said vertical guide wall to smooth said flap and squeeze out any surplus moisture.

7. In an envelop sealing machine, the combination with means for successively moistening the gummed flaps of envelops and simultaneously feeding the latter endwise in a substantially vertical plane, of a pair of sealing rolls between which the envelops pass to seal the flaps, said sealing rolls being mounted on axes slightly inclined from the vertical whereby the envelops are delivered in a slightly sidewise canted position so that they uniformly fall the same side up.

ALBERT B. CRAWFORD.
